 Delta Electric Company, Marion, Ind., a corporation of Indiana

Application September 21, 1944, Serial No. 555,061

6 Claims. (Cl. 200—60)

1

This invention relates to flashlights and has for its principal object the provision of a flashlight which may be submerged in water without deleteriously affecting the operating characteristics thereof.

Objects of the present invention include the provision of a flashlight in which all operating parts which are liable to be adversely affected by moisture, as by for instance submersing the flashlight in water, are protected from contact by moisture, as by for instance submersing the flashlight in water; the provision of a flashlight in which the battery or batteries, lamp bulbs, and contacts in the circuit between the battery or batteries and the lamp bulb, including the switch contacts, are sealed from contact with water; the provision of a flashlight including a casing containing batteries and a lamp together with switch elements for controlling the circuit to the lamp which are contained within a waterproof casing, and means operable from the exterior of the casing are provided for operating the switch contacts; the provision of a construction as last described in which the switch contacts are operated through the medium of a plunger projecting through an opening in the casing, the plunger being sealed to the casing to prevent the passage of moisture between it and the casing; the provision of a switch construction for flashlights in which the seal between the plunger and the casing comprises a washer of rubber-like material sealed at its radially inner margin to the plunger and at its radially outer margin to the casing; the provision of a construction as above described in which the opening in the casing through which the plunger projects is stepped whereby to form an annular shoulder for receiving the washer of rubber-like material; the provision of a construction as last described including spring means cooperating between the washer of rubber-like material and the plunger constantly urging the plunger toward inoperative position and the washer towards sealing engagement with the casing; and the provision of a construction as above described in which the plunger is provided with a peripheral groove in which the radially inner margins of the washer are received.

The above being among the objects of the present invention the same consists in certain novel features of construction and combinations of parts to be hereinafter described with reference to the accompanying drawing, and then claimed, having the above and other objects in view.

In the accompanying drawing which illustrates

2

a suitable embodiment of the present invention and in which like numerals refer to like parts throughout the several different views,

Fig. 1 is a vertical sectional view taken diametrically through a flashlight embodying the present invention and showing the switch mechanism in the position in which it is locked against switch operation by radially inward movement of the operating member;

Fig. 2 is an enlarged fragmentary, sectional view taken in the same plane as Fig. 1 showing the switch operating member in full lines in the same position as in Fig. 1, and in dotted lines in the position in which it is possible to close the switch by radially inward movement of the operating member;

Fig. 3 is a view similar to Fig. 2 but illustrating the switch operating member in the position in which it assumes when moved to maintain the switch in closed position;

Fig. 4 is a fragmentary, transverse sectional view taken on the line 4—4 of Fig. 2; and,

Fig. 5 is a slightly reduced, fragmentary, transverse sectional view taken on the line 5—5 of Fig. 2.

The present invention relates to waterproof flashlight constructions in which the circuit to the lamp bulb may be controlled by an operating member positioned exteriorly of the flashlight. Inasmuch as various types of waterproof casings may be provided it will be appreciated that the feature of the invention relates particularly to the means which permits the circuit to be controlled by a movable member on the exterior of the casing without danger of leakage of water to the interior thereof.

Referring now to the drawing, the particular flashlight construction to which the present invention is shown applied comprises a casing consisting of a main body portion 10 of hollow tubular construction open at both ends and formed of electrical insulating material such as, for instance, moldable plastic material, rubber or rubber composition, or the like. The rear end of the casing 10 is closed by an imperforate cap member 12 screw threaded thereon and sealed against leakage with respect to the main body portion 10 by means of a resilient gasket 14 interposed between its forward edge and an annular shoulder 16 formed in cooperative relationship with respect thereto on the main body portion 10.

The forward end of the casing 10 is, of course, equipped with a transparent closure which may be either of the flat or of a lens type construction

and may be secured and sealed to the main body 10 in any suitable manner. In the present case and as is preferable a lens type of closure is shown as comprising a lens portion 13 having formed integrally and concentrically therewith at its periphery a rearwardly directed internally threaded ring portion 20 which is threadably received upon the forward end of the body 10. The ring portion 20 thus serves as a mounting ring for the lens portion 13 and being formed integrally therewith is arranged in sealed relation with respect thereto. As in the case of the rear closure 12, a resilient washer 22 is interposed between the rear edge of the ring portion 20 and an opposed annular shoulder 24 formed on the body 10, thus sealing this end of the body 10 in a water-tight manner.

A conventional metal reflector 26 provided with a radially outwardly directed annular flange 28 is held in position within the lens and ring assembly 13-20 by reason of the flange 28 being confined between the forward edge of the body 10 and the rear face of the lens portion 13 as shown. The reflector 26 is conventionally provided centrally thereof with a rearwardly projecting threaded metallic sleeve 30 fixed thereto in which the base 32 of a lamp bulb 34 is threadably received, the lamp base 32 terminating in a conventional contact 36. A cup-shaped member 38 formed of insulating material is threaded exteriorly over the sleeve 30 from the rear end thereof and is centrally provided in its rear wall with a contact 40 which is electrically connected to the contact 36 of the bulb base 32 by means of a coil spring 42 held under compression between the contacts 36 and 40. Within the main body 10 is positioned one or more conventional flashlight batteries 44, shown as two by way of illustration. The carbon 46 of the outermost battery 44 is pressed against the contact 40 and the carbon 46 of the rearmost battery 44 is pressed against the bottom of the forward battery 44 by means of a coil spring 48 maintained under compression between the bottom of the rearmost battery 44 and the end wall of the cap 12. The coil spring 48 is preferably of the frusto-conical type, the endmost coil of which at the large end thereof is of a sufficient diameter to be frictionally received by the side walls of the cap 12 adjacent the end wall thereof.

Received within the rear end of the bore of the main body portion 10 is a metal ring 50 provided with a radially outwardly directed flange 52 at its rear end which overlies the rear edge of the main body portion 10. The large turn of the coil spring 48 is provided with an axially and radially inwardly bent free end portion 54 which, when the cap 12 is assembled to the main body 10, constantly bears against the ring 50, thus establishing electrical contact between these two parts.

A strip conductor element 56 which extends longitudinally of the main body 10 on the interior thereof is electrically connected at its rear end to the metal ring 50 by means of a rivet 58. The conductor 56 extends forwardly from the rivet 58 and in normally contacting relationship with respect to the bore of the main body 10 at a point approximately in transverse or radial alignment with the shoulder 26. Intermediate its ends it is additionally secured to the main body 10 by means of a rivet 60 and forwardly of the rivet 60 is guided between a pair of inwardly projecting ribs or beads 61 formed integrally with the main body 10. Forwardly of

5 the forward end of the conductor 56 a bracket 62 positioned in the bore of the main body 10 is secured to the main body 10 by means of a rivet 64. The bracket 62 is provided with a circumferentially directed extension 66 and a rearwardly directed and radially inwardly offset extension 68. As best brought out in Fig. 4 the extension 66 is not concentric with the bore of the main body 10 but its free end is bent radially inwardly as indicated in Fig. 4 so that when threading the lens ring combination 13-20 upon the main body 10 the reflector 26 is forced into yielding engagement with the extension 66, thus to establish electrical contact between them.

It will be noted that the rearward extension 68 projects down under the free forward edge of the conductor 56 and is normally spaced therefrom, but that when the free forward end of the conductor 56 is flexed radially inwardly as indicated in Fig. 3 it will contact the extension 66 and thus establish electrical contact between it and the extension 68. This last feature constitutes the electrical switch for the circuit through the lamp 34 and batteries 44. In other words, the extension 66 is electrically connected through the bracket 62, the extension 66, and reflector 26 to the exterior of the lamp bulb base 32 and which is connected through the lamp filament 34a with the contact 36. The contact 36 is electrically connected to the spring 42 and contact 40 with the carbon 46 for the forward battery 44. The bottom of the rear battery 44 is connected through the spring 48 and its end 54 with the ring 50 and through the rivet 58 to the conductor 56, this being movably associated with the extension 66 to control the opening or closing of the circuit thus described.

The construction thus far described may, in the broader aspects of the invention, be any conventional construction in which the batteries, the lamp and the circuit between the batteries and the lamp including the switch contacts for the circuit are sealed within the flashlight casing in water-tight relation. In other words, as far as the broader aspects of the invention are concerned all that is necessary is that a switch contact sealed within a water-tight casing be capable of being moved to close the electrical circuit by means of a plunger projecting through a wall of the casing. In the present case that portion of the conductor 56 forwardly of the rivet 60 constitutes the movable element of the switch which is to be operated and this is accomplished as follows.

55 The wall of the main body 10 adjacent its forward end is thickened as at 70 over a limited circumferential extent best indicated in Fig. 5. This thickened portion 70 is provided with a radial opening or hole 72 therethrough in forwardly spaced relation with respect to the rivet 60 and in radial alignment with the conductor 56. The hole 72 is counterbored as at 74 from its outer end thus forming an annular shoulder 76 within the bore intermediate the ends thereof. A plunger 78 is positioned centrally of the bore 72 and in materially spaced relation with respect to the walls thereof. The plunger 78 is provided with a disc-like head 80 of a diameter to be relatively closely but axially slidably received in the counterbore 74. A coil spring 82 received in the counterbore portion 74 constantly acts against the head 80 of the plunger 78 to urge it in a radially outwardly direction. It will be appreciated that radially inward movement of the plunger 78 will force the plunger against the con-

ductor 56 and upon sufficient force being exerted in this direction will cause the free forward end of the conductor 56 to be brought into contact with the extension 68 of the bracket 62, thereby to complete the electrical circuit through the lamp 34.

In accordance with the present invention in order to seal the space between the plunger 78 and the body portion 10 against the passage of water or moisture to the interior of the flashlight the following mechanism is provided. A resilient washer 84 of rubber or rubber-like material is arranged in surrounding and preferably contracted relation upon the plunger 78, and its peripheral margin is closely received in the counterbore 74 against the shoulder 76. A metal washer 86, of a size preferably closely fitting the counterbore 74 and with its central hole providing a material amount of clearance between it and the plunger 78, is positioned over the washer 84. The coil spring 82, where the washer 86 is employed, presses the washer 86 downwardly against the rubber washer 84 and the latter firmly against the shoulder 76 and at the same time tends to radially expand the washer 84 so as to firmly seal it against the bore of the counterbore 74. A similar effect is obtained where the metal washer 86 is eliminated. As will be appreciated this effects a water-tight seal between the rubber washer 84 and the body portion 10.

Where the plunger 78 is not peripherally grooved as shown, then its central opening is of a size smaller than the diameter of the plunger 78 so as to be expanded from its normal or free size by projection of the plunger 78 therethrough, thus to provide a water-tight seal between the washer 84 and the plunger 78. Preferably, however, the plunger 78 is provided with a peripheral groove 88 in which the margins of the rubber washer 84 surrounding the central hole therein are received. The groove 88 may be of an axial dimension less than the thickness of the rubber washer 84 so that the inner margins of the washer are compressed axially of the plunger 78 in being received within the groove 88, and preferably the diameter of the grooved portion of the plunger 78 is slightly larger than the free diameter of the hole in the washer 84, thus to provide a maximum sealing effect between the washer 84 and the plunger 78.

The washer 84 being formed of readily yieldable and resilient material and being sealed both to the main body 10 and the plunger 78, it will be appreciated that it forms an effective seal between the plunger 78 and the main body 10 preventing the passage of moisture and/or water between it and the main body 10 from the exterior to the interior of the flashlight casing. Furthermore, the washer 84 being radially unsupported intermediate its inner and outer margins, its central portion is capable of being flexed axially with respect to its peripheral margins so that it does not provide any undue resistance to movement of the plunger 78 required to operate the switch mechanism for the flashlight.

While the mechanism thus far described is sufficient to permit opening and closing of the circuit to the lamp bulb 34 from the outside of the casing without danger of moisture finding its way between the plunger 78 and the body portion 10, particularly if means are provided for limiting undesirable outward movement of the plunger 78 under the influence of the spring 82, additional means are preferably employed for enabling the selective operation of the plunger 78 either to

momentarily hold the switch contacts in closed position, hold them in closed position for any desired period of time, or to prevent operation of the plunger 78. The mechanism provided for this purpose will now be described.

An inverted pan-like member 90 formed from sheet metal and having an outwardly directed peripheral margin or flange 92 is positioned over the thickened portion 70 and is secured thereto by means of screws 94 projected through its end portion and threaded preferably into metallic nuts 96 molded into the thickened portion 70. The part 90 is centrally provided in its top wall with a longitudinally extending slot 98. Confined under the member 90 and between the member 90 and the head 80 of the plunger 78 is an operating member indicated generally at 100 provided with an upward projection forming a thumbpiece 102 which projects up through the slot 98. The thumbpiece 102 is of less length, longitudinally of the flashlight, than the slot 98 so that it may be moved longitudinally of the slot 98 thereby to move the element 100. It will be appreciated that the member 90 acting through the element 100 limits outward projection of the plunger 78 under the force of the spring 82. The top wall of the member 90 rearwardly of the rear end of the slot 98 is depressed to form an inward projection 104 and the upper face of the operating element 100 is provided with a complementary groove 106 therein in such position that it interferes with the projection 104, under the force of the spring 82, when the operating element 100 is at its extreme position to the rear of the slot 98 as shown in full lines in Figs. 1 and 2. The interengagement of the projection 104 and the groove 106 thus resiliently locks the member 100 in the corresponding position.

The operating element 100 is provided on its bottom face with a downward projection 108 adjacent its forward end and a similar projection 110 adjacent its rear end. When the operating element 100 is in the position illustrated in full lines in Figs. 1 and 2 any attempt to depress the operating element 100 radially inwardly by pressure on the thumbpiece 102 will bring the projections 108 and 110 into contact with the upper face of the body 10 before the plunger 78 can be depressed sufficiently to cause the free forward end of the conductor strip 56 to contact the extension 68 and close the circuit to the flashlight. Thus when the operating element 100 is in the position described it is impossible to close the circuit of the flashlight by inward pressure applied to the thumbpiece 102.

Forwardly of the projection 110 the operating element 100 is provided on its lower face with a boss or pimple 112. The head 80 of the plunger 78 is centrally provided in its upper face with a depression 114. If the operating member 100 is operated, through the thumbpiece 102, forwardly from the position illustrated in full lines in Fig. 2 to the position illustrated in dotted lines in that figure, the pimple 112 will be brought into alignment with the depression 114, the plunger 78 yielding against the force of the spring 82 as the pimple 112 rides over the head 80 of the plunger 78 to bring it to such position. This is the position for operating the switch by direct inward pressure on the thumbpiece 102. To permit this to be done without interference between the projections 108 and 110 on the bottom face of the operating element 100 with the upper face of the thickened portion 70 of the main body 10, such upper face of the thickened portion 70 is pro-

vided with a groove or depression 120 in vertical alignment with the projection 108 when in the last-mentioned position and a groove or depression 122 in line with the projection 110 when in the last-mentioned position. These grooves or depressions 120 and 122 provide sufficient space or clearance for reception of the projections 108 and 110 to permit the plunger 78 to be actuated by downward pressure on the operating element applied to the thumbpiece 102 to bring the forward free end of the conductor 56 into contact with the extension 68 of the bracket 62.

If it is desired to close the circuit to the flashlight without applying and maintaining downward pressure on the thumbpiece 102, then the thumbpiece 102 is actuated to move the operating element 100 to its extreme forward position in which the thumbpiece 102 abuts the forward end of the slot 56, as illustrated in Fig. 3. In this position of the parts the projection 112 on the rear end of the operating element 100 rides up on the head 80 of the plunger 78 and causes it to be depressed sufficiently to move the conductor element 53 into contact with the extension 68, thereby to close the circuit through the bulb 34, as illustrated in Fig. 3.

It will be appreciated, and as particularly brought out in Fig. 3, that when the plunger 78 is depressed to close the circuit for the flashlight as above described the sealing washer 84 will yield to permit such movement but without affecting the seal between the plunger 78 and the body 10 in any respect whatever. The construction thus provides a simple and effective means whereby the passage through the body for the plunger 78 is rendered waterproof, and where such construction is employed in a flashlight of the type shown including a waterproof casing within which all of the electrical connections, contacts and elements are located, submersion in water will have no effect on the operativeness of the device.

Having thus described my invention, what I claim by Letters Patent is:

1. In a flashlight having a casing provided with an opening therethrough and otherwise sealed against the entrance of water and a movable switch element positioned within said casing, means for actuating said switch element through said opening, said means comprising a switch-actuating member extending from the exterior of said casing axially through said opening and into operative engagement with said switch element, and a flexible resilient washer-like element of water impervious material positioned within said opening and having its outer margin in sealing engagement with the internal walls of said opening and its inner periphery surrounding and in sealing engagement with said actuating member to thereby seal said opening, at least the outer portion of said opening being of substantially the same size as the outer periphery of said washer-like element to provide for ready insertion of said washer-like element into sealing position in said opening, said actuating member being radially spaced from said inner walls of said opening adjacent said flexible element to provide for axial distortion of said flexible element and for axial movement of said actuating member to operate said switch element.

2. In a flashlight having a casing provided with an opening therethrough and otherwise sealed against the entrance of water and a movable switch element positioned within said casing, means for actuating said switch element through

5 said opening and for sealing said opening, said means comprising a switch-actuating plunger extending from the exterior of said casing axially through said opening and into operative engagement with said switch element, and a flexible resilient washer-like element of water impervious material positioned within said opening and having its outer margin in engagement with the external walls of said opening and its inner periphery contractably surrounding said actuating member to seal said opening, means within said opening to hold said margin in sealing engagement with said internal walls, said actuating member being radially spaced from said inner walls of said opening adjacent said flexible element to provide for axial distortion of said flexible element and for axial movement of said actuating member to operate said switch element.

3. In a flashlight having a casing provided with a thickened wall portion having a bore therethrough, said casing being otherwise sealed against the entrance of water, and a movable switch element positioned within said casing, means for actuating said switch element through 20 said bore and for sealing said bore, said means comprising a plunger extending from the exterior of said casing through said bore into operative engagement with said switch element, said bore having an inner portion adjacent the 25 interior of said casing of smaller diameter than an outer portion of said bore adjacent the exterior of said casing to provide an outwardly directed shoulder in said bore between said portions, a flexible resilient washer-like element of 30 water impervious material positioned within the outer portion of said bore and having its outer margin resting on said shoulder, means within 35 said bore for pressing said outer margin against said shoulder to seal said flexible element to the 40 walls of said bore, said flexible element having its inner periphery surrounding said plunger in sealing engagement therewith to thereby seal said opening, said plunger being of smaller diameter than said inner portion of said bore adjacent said 45 shoulder to provide for axial distortion of said flexible member and for axial movement of said plunger through said bore to operate said switch element.

4. In a flashlight having a casing provided with 50 a thickened wall portion having a bore therethrough, said casing being otherwise sealed against the entrance of water, and a movable switch element positioned within said casing, means for actuating said switch element through 55 said bore and for sealing said bore, said means comprising a plunger extending from the exterior of said casing through said bore into operative engagement with said switch element, said bore having an inner portion adjacent the 60 interior of said casing of smaller diameter than an outer portion of said bore adjacent the exterior of said casing to provide an outwardly directed shoulder in said bore between said portions, a flexible resilient washer-like element of 65 water impervious material positioned within the outer portion of said bore and having its outer margin resting on said shoulder, means within said bore for pressing said outer margin against said shoulder to seal said flexible element to the 70 walls of said bore, said plunger having a head slidably engaging in the outer portion of said bore and a shank portion of smaller diameter than said head extending through said inner portion of said bore, said flexible element having its inner periphery contractably engaging the

shank portion of said plunger to thereby seal said bore, the shank portion of said plunger being substantially smaller in diameter than the inner portion of said bore to provide for axial distortion of said flexible member and for axial movement of said plunger to operate said switch element.

5. In a flashlight having a casing provided with a thickened wall portion having a bore therethrough, said casing being otherwise sealed against the entrance of water, and a movable switch element positioned within said casing, means for actuating said switch element through said bore and for sealing said bore, said means comprising a plunger extending from the exterior of said casing through said bore into operative engagement with said switch element, said bore having an inner portion adjacent the interior of said casing of smaller diameter than an outer portion of said bore adjacent the exterior of said casing to provide an outwardly directed shoulder in said bore between said portions, a flexible resilient washer-like element of water impervious material positioned within the outer portion of said bore and having its outer margin resting on said shoulder, said plunger having a head slidably engaging in the outer portion of said bore and a shank portion of smaller diameter than said head extending through said inner portion of said bore, a spring positioned within said bore between said head and the outer margin of said flexible element, means for holding said head in the outer portion of said bore to compress said spring and resiliently press said outer margin of said flexible element against said shoulder to seal said flexible element to the walls of said bore, said flexible element having its inner periphery contractably engaging the shank portion of said plunger to thereby seal said bore, the shank portion of said plunger being substantially smaller in diameter than the inner portion of said bore to provide for axial distortion of said flexible member and for axial movement of said plunger to operate said switch element.

6. In a flashlight having a casing provided with a thickened wall portion having a bore therethrough, said casing being otherwise sealed against the entrance of water, and a movable

switch element positioned within said casing, means for actuating said switch element through said bore and for sealing said bore, said means comprising a plunger extending from the exterior of said casing through said bore into operative engagement with said switch element, said bore having an inner portion adjacent the interior of said casing of smaller diameter than an outer portion of said bore adjacent the exterior of said casing to provide an outwardly directed shoulder in said bore between said portions, a flexible resilient washer-like element of water impervious material positioned within the outer portion of said bore and having its outer margin resting on said shoulder, said plunger having a head slidably engaging in the outer portion of said bore and a shank portion of smaller diameter than said head extending through said inner portion of said bore, a spring positioned within said bore between said head and the outer margin of said flexible element, plunger actuating means movable longitudinally of said casing and holding said head in the outer portion of said bore to compress said spring and resiliently press said outer margin of said flexible element against said shoulder to seal said flexible element against the internal walls of said bore, the shank of said plunger having an annular groove therein, said flexible element having its inner periphery contractably engaged in said groove to thereby seal said bore, the shank portion of said plunger being substantially smaller in diameter than the inner portion of said bore to provide for axial distortion of said flexible element and for axial movement of said plunger to operate said switch element.
